PORTABLE STARTING GATE WITH FIXED STALLS

August T. J. Bahr, St. Louis, Mo., assignor to
Bahr Starting Gate Corporation, Chicago, Ill.,
a corporation of Illinois

Application April 25, 1932, Serial No. 607,246

5 Claims. (Cl. 119—15.5)

This invention relates to an improved portable starting gate such as those used at race tracks or for training race horses or the like, and has for one of its principal objects the provision of a starting gate of this type which shall be superior to those now in use in both simplicity of construction and ease of operation.

One of the important objects of this invention is to provide a portable starting gate for race tracks and the like which shall be considerably lighter in weight than the gates now in use while at the same time possessing added advantages of relatively greater strength and more adequate portability.

Another important object of the invention resides in the provision of a starting gate wherein the partitions forming the stalls for separating the horses preparatory to starting the race are made fixed with respect to the gate structure itself and are constructed so as to depend from an overhead U-shaped support in such a manner as to positively avoid any shifting, twisting, or lateral motion of the partitions even under the most extraordinary conditions of plunging, kicking, and even falling horses.

Another and still further important object of the invention is the provision of a starting gate which while strong and durable is considerably lighter and constructed with elements of great portability, so that the same can be readily shifted onto and off of the track as occasion arises and necessity demands, in a minimum time and by the exercise of a relatively small amount of labor.

Another object of the invention peculiar to the present construction is the provision of hinged end stall sections which besides eliminating considerable weight afford a much lighter structure and further allow of the turning of the device in a very short radius.

Another and still further important object of the invention lies in the wheel mountings or supports for the structure whereby the axle for one set of wheels is pivoted for substantially universal movement in a horizontal plane for very short turns, while the other set of wheels are mounted on an axle relatively fixed with respect to the structure, so that a correct tracking of that end of the structure will necessarily follow with respect to the original direction or directions of motion imparted to the other end.

Still another and further important object of the invention is embodied in the particular structure of the padded coverings for the partitions themselves with especial reference to the construction of such pads and the application of the same to the partition frames.

Other and further important objects of the invention will be apparent from the disclosures in

the accompanying drawings and following specification.

The invention, in a preferred form, is illustrated in the drawings and hereinafter more fully described.

In the drawings:

Figure 1 is an elevational view of the improved starting gate of this invention, showing particularly the fixed central partitions forming the stalls, the U-shaped partition supporting frame, and the hinged end partition sections.

Figure 2 is a top plan view of the pivoted axle mounting, showing particularly the ball bearing anti-friction construction, and also the dust cap and removable tongue construction.

Figure 3 is an elevational view of what is known as a training gate, these gates being made on the same principles as the gate shown in Figure 1, but with a much smaller number of stalls.

Figure 4 is an end view of a partition and a portion of a depending support showing the reinforced partition frame.

Figure 5 is a side view of the partition and a portion of the support showing the partition as covered with padding.

Figure 6 is a side view of a partition frame with the padding removed, and showing the interior reinforcing braces.

Figure 7 is an end view of a starting gate showing the pivoted axle mounting.

Figure 8 is a view of the other end of the gate, illustrating the fixed axle mounting.

Figure 9 is a top plan view of a piece of the partition padding showing one of the steps in the construction thereof.

Figure 10 is an enlarged sectional view of a portion of stall padding showing the same in another step of the process of manufacture.

Figure 11 is a sectional view of the padding showing the same after the compressing and stitching operations.

Figure 12 is a perspective view showing a portion of the top and one end of the padding after application to a stall frame.

Figure 13 is a bottom view of a section of padding applied to a stall frame.

As shown in the drawings:

The reference numeral 14 indicates generally the supporting frame of the improved starting gate of this invention, the same being formed of integral U-shaped elements as best shown in Figure 1, having cross braces 16 and 18 extending throughout their length and depth respectively, and it will be noted that the structure eliminates the use of end bars as the overhead structure is simply bent down at the ends to form supports which are then mounted on platforms 20 and 22 respectively.

The platform 20 is supported by a pair of movable wheels 24 mounted over an axle 26 and

upon this axle is fixed a support 28 which cooperates with the platform 20.

In the center of the support 28 is a metal plate or the like 30 preferably circular in shape and having openings 32 therein for the reception of ball bearings 34 which are likewise fitted into suitable corresponding openings in a plate 36 forming the bottom of the platform or support 20.

10 At the front of the platform 28 is a socket or housing 38 into which is adapted to be positioned the end of a tongue or the like 40 by means of which the device can be drawn or propelled from place to place, and this tongue has near one end an opening through which passes a pin 42 when the opening is aligned with a corresponding opening in the top of the housing 38. In this way, the whole device can be propelled or drawn from place to place, and a desired directional effect imparted to the guiding wheels 24.

15 It will be noted that suitable provisions are made for preventing access of dust, dirt, or other foreign material to those portions of the axles 26 upon which the wheels are mounted, these 20 preferably being supported on roller or ball bearings which are protected at the inner faces of the wheels by suitable retaining plates 44 and by dust caps 46 mounted on correspondingly screw-threaded ends 48 of the axles themselves.

25 30 A plurality of relatively fixed stall partitions or the like 50 are supported from the overhead member 14, these partitions being fixed in position by means of depending frame structures 52, these frame structures being composed of downwardly extending elements which gradually converge as best shown in Figures 1 and 4, and in 35 order to prevent twisting torque or any movement due to undue strains and stresses, cross braces 54 are provided for each downwardly extending stall support. These members are preferably tubular.

40 These cross braces extend both transversely and longitudinally as shown in Figures 1 and 5 respectively.

45 Each partition 50 is formed in a downwardly tapering shape as best illustrated in Figures 1 and 4, and in addition to comprising the side members also includes top cross braces 56, bottom connecting elements 58, and central vertically extending ties 60 whereby a very substantial and rigid stall or partition results.

50 Each stall element is fastened in position to the downwardly extending supports 52 first by means of a longitudinally extending connecting element 62 as best shown in Figure 6 and also by additional transverse connections extending at the top and bottom of the partition structure and adjacent the lower ends of the struts 52. By means of this reinforced construction, a twisting or bending moment applied at the outermost ends of a partition structure will have but very little, if any effect, even though this twisting or bending force be greatly in excess of that which would be produced by the rushing, plunging, or falling of a horse or horses thereagainst. The downwardly extending structures 52 are so thoroughly reinforced by the cross braces 54 that no perceptible twisting or torque results from the application of such end forces, and the braces also 55 act to effectively prevent any side sway or lateral movement of the partitions with respect to the frame or to each other.

60 It will be noted that the downwardly extending ends of the U-shaped overhead structure are also braced in one direction by means of rein-

forcing elements 64 and 66, and in the other direction by means of cross reinforcing elements 68 and also by horizontally extending braces 70.

65 The end of the structure opposite the movable axle is supported on a fixed axle 72 as best shown in Figure 8 upon which is mounted a set of wheels 74, and this fixed axle is supported in position with respect to the platform 22 by means of struts 76 and V-braces 78. These V-braces are secured at their ends to the axle 72 10 by means of clamps or the like 80.

70 It will be noted that the partitions 50 are of a sufficient width so as to enable an assistant starter to stand in front of a stall and be protected against accidental impact of a horse when 15 the rush of the horses from the space between two stalls ensues, owing to the springing of the barrier. This relatively wide stall construction adequately protects the assistant starters while at the same time taking but very little additional 20 space, and on account of the reinforced braced construction of the stalls and the supports themselves, actually results in a saving of weight.

75 In order to allow of the complete turning of the axle 26 about its pivot point 82, the stall member 84 adjacent that end of the starting gate is pivoted at 86 whereby the same can be raised into a position shown in dotted lines in Figure 1 and locked in that position by means of a latch 88 pivotally mounted on the end of the partition and adapted to cooperate with a suitable retaining staple 90 when in lowermost position, and with a corresponding retaining staple 92 when in upper position. A similar structure is provided for the stall partition 94 at the other end of the gate. This, of course, is not absolutely necessary as the wheels 74 are relatively fixed, and this partition 94 may be built as fixed in position, if so desired.

80 A similar construction such as overhead U-shaped supporting elements 15 and cross braces 17 is followed in the practice or training gate shown in Figure 3, this also having depending stall supports 53 provided with braces 55 and which support stalls or partitions 51 in the manner heretofore described. A set of pivotally mounted wheels 25 is provided on this gate and a set of fixed wheels 75.

85 Also there is provided a hinged end partition 85 operating in the same manner as the stall element 84. Suitable brace elements 65 and 67 respectively are provided for the downwardly depending ends of the U-shaped overhead structure, and these ends are mounted on platforms 21 and 23 respectively.

90 The low partitions and also the open-work end structures and the restricted shape of the supports for the stalls allow a considerably extended vision of the horses themselves when in the gate, and the fact that folding partitions are employed at the ends reduces the number of hanger structures. The fact that one set of wheels is fixed insures a proper alignment of the wheels when the structure is in motion, and the stalls and supports are so constructed that no whip will result even under very sudden or jerky starting. The starter himself has a considerably better vision of all the horses when in a gate of this type.

95 In Figures 9 and 10 is shown the first step in 76 the preparation of the padding for the partitions wherein a bottom double layer of strong canvas or duck is provided as shown at 57, and three layers of cotton are superimposed thereon as illustrated at 59, after which a top single layer of 75

duck 61 is laid thereon in the nature of a covering, after which the same are compressed and then stitched together by means of stitches as best shown at 63 in Figure 9.

5 These lines of stitches are preferably such as to produce squares, triangles, or diamond-shaped tufts of the compressed material whereby the accidental kicking of the padding by the horses will result in only a very small cut or tear which can 10 be easily repaired and which will not be liable to become extensive. The stitching 63 is accomplished in such a manner that the entire padding and particularly the cotton filling is compressed as best shown in Figure 11, whereby much stronger 15 construction results, and one which has a very suitable cushioning effect, thereby protecting the horses and riders against injury.

The pads are sheathlike and of such dimensions as to fit snugly around the bottoms, sides and over 20 the tops of the partitions as best shown in Figure 12 and are also provided with end members 69 whereby the entire stall is closed in or thoroughly covered by the padding itself. The upper ends of 25 the padding are provided with eyelets 71 through which are entwined laces or the like 73, so that the same can be pulled into a close fit with the framework of the stall, thereby insuring an adequate covering and one which will not be likely to become loose or displaced even under the most 30 severe usage. Extra cushioning elements are shown at 90.

As best shown in Figure 13 a series of openings 35 protected by annular brass collars 77 are provided in the padding adjacent the bottom of the partition structure so as to allow for proper drainage of any water or the like which may accidentally find its way into the interior of the partition through the interstices of the lacing 73.

The entire gate is much lighter in weight than 40 any heretofore used while at the same time being actually stronger, this being due to the special brace construction, and the fact that the partitions are fixed in position by means of depending supports, which themselves are braced 45 in every direction against twisting, provides a very rigid and satisfactory device which will withstand the most severe conditions of use and abuse.

Furthermore, the open framework peculiar to 50 this particular structure coupled with the relatively low partitions enables a very good view of all the horses at all times by both the public and the officials, thereby providing a more satisfactory apparatus. The fact that the wheels at 55 one end only are mounted on a pivoted axle while at the same time allowing for a turning movement throughout practically three hundred and sixty degrees provides a readily portable gate which will not be subject to vasillations of direction due 60 to all wheels being swiveled, and at the same time, this construction eliminates the use of two or three additional helpers which were always necessary with the old type gate. The height of the fixed partitions from the ground prevents spattering or saturating of the padding with mud or water, and at the same time, the partitions are so constructed that it is impossible for a horse to get his feet caught under the gate. The padding can be easily removed, if necessary, for cleaning or repairs, and as readily replaced, and furthermore, is of such a construction that it is tough and rugged, and will withstand a considerable 65 number of hard knocks.

I am aware that many changes may be made

and numerous details of construction varied throughout a wide range without departing from the principles of this invention, and I, therefore, do not purpose limiting the patent granted hereon otherwise than as necessitated by the prior art. 5

I claim as my invention:

1. A portable starting gate, including an inverted U-shaped overhead structure, supports for the ends of the structure, and wheels mounted on the supports, together with a series of stall partitions depending from the overhead structure, and a pair of end stall partitions mounted adjacent the ends of the overhead structure and extending below the top edge of the wheels, at least one of said stall partitions being hingedly 10 mounted on the overhead structure, and means for locking said stall partition at the limit of its upward movement about the hinge to allow the turning thereunder of the wheels on the pivoted 15 axle. 20

2. In a portable starting gate, having an overhead trussed structure, and a series of trussed partitions forming stalls fixedly dependent from the overhead structure; each of said partitions comprising a rigid framework and a padded covering 25 for the framework, said padded covering comprising outer layers of heavy canvas, and an inner filling of relatively soft material such as cotton, and a series of diagonal and transverse lines of stitching connecting the outer layers and the 30 filling into a unitary covering, eyelets adjacent to the edges of the covering, and lacing means passing through the eyelets for securing the covering in position on a partition. 35

3. In a portable starting gate, having an overhead trussed structure, and a series of trussed partitions forming stalls fixedly dependent from the overhead structure; each of said partitions comprising a rigid framework and a padded covering 40 comprising outer layers of heavy canvas, and an inner filling of relatively soft material such as cotton, and a series of diagonal and transverse lines of stitching connecting the outer layers and the 45 filling into a unitary covering, eyelets adjacent to the edges of the covering, and lacing means passing through the eyelets for securing the covering in position on a partition, together with drainage openings in that portion of the covering adapted to be located adjacent the bottom of the partition. 50

4. In a portable starting gate having an overhead structure and a series of depending supports mounted on the overhead structure, each support consisting of a trussed frame and a partition connected to the lower end of the trussed frame, cross braces in the support for preventing twisting movement, a padding on each partition, each partition comprising a trussed structure and connected adjacent its bottom with the 60 end of the trussed frame. 55

5. In a portable starting gate, having an overhead structure and a series of depending supports mounted on the overhead structure, each support consisting of a trussed frame tapering 65 downwardly, and a partition connected to the lower end of the trussed frame, cross braces in the support for preventing twisting movement, a padding on each partition, each partition comprising a trussed structure, and also tapering 70 downwardly and connected adjacent its bottom with the end of the trussed frame. 75

AUGUST T. J. BAHR.
